LOOSE LEAF STRUCTURE

John Schade, Holyoke, Mass., assignor to National
Blank Book Company, Holyoke, Mass., a cor-
poration of Massachusetts

Application August 11, 1934, Serial No. 739,447

12 Claims. (Cl. 129—8)

This invention relates to improvements in loose leaf structure. It may be used for holding a pack or filler of sheets and it may or may not be supplied with covers hinged to the loose leaf structure. The improvements are disclosed in their preferred form as applied to a binder such as shown in my prior Patent No. 1,954,494 of April 10, 1934. The features of the present invention have particular importance in improving the operation of the type of binder shown in said prior patent, but they are not limited to that use. This will appear in the description and claims.

Since the construction and operation of the parts of the specific disclosure herein are in some respects and up to a certain point quite similar to those fully described in my prior patent, I will only show them here in a general way and confine the particulars and detailed description to the new features.

Fig. 1 is a plan view of a complete loose leaf binder (except for the cut-away cover portions) in reading position with the improvements added;

Fig. 2 is a section on line 2—2 of Fig. 1 but with the binder in position for manipulating the loose leaf contents for changes;

Fig. 3 is a side view of a latch construction;

Fig. 4 is a top view of the same;

Fig. 5 is a section on line 5—5 of Fig. 1;

Fig. 6 is a plan view of one of the guide mem-

bers; and

Fig. 7 is a section on line 7—7 of Fig. 6.

The binder shown is made up with flat back plates 1 and 2, having side flanges 14, posts 30 and 31, and covers 3 and 4. In a general way these parts may be made up as in my prior patent and for the same purpose.

On the inner margin of plate 2, I provide an overhanging flange 75 with a cross-section as seen in Fig. 2. The outer edge is rolled as a hinge eye to receive a round rod 76 which lies in the eye as in a loose bearing. The end portions 77 of flange 75 overlie adjacent guide members 78 fixed at the end edges of plate 1. It will be clear from the drawing (Fig. 5) that the ends of rod 76 are guided (as plates 1 and 2 slide in overlapping relation) between the upper and lower plates of members 78 (Fig. 7). The upper plates each have a hook-shaped return bend 78' to receive and stop the travel of plate 2 by engaging the ends of rod 76. In this extreme position of the sliding plates 1 and 2 the parts 78 and the ends of rod 76 are in position to act as a hinge. Thus plates 1 and 2 may turn into the position of Fig. 2 which is most desirable for manipulating the sheets. The shape of flange 75 permits

the small angle C for the parts, as shown in Fig. 2. This is an advantage in bringing posts 30 and 31 more nearly vertical so as to permit the sheets on each side to lie out more nearly flat on the covers as compared to the prior art structure.

The lower plates of members 78 are extended inwardly of plate 1 and riveted to the latter. On one margin of each lower plate (Fig. 6) I provide a gear rack 79 economically punched out of the plate metal.

To engage these racks I fasten gears 81 to rod 76. It is convenient to key the gears to the rod but, as the rod is free to rotate in its bearing without applying force anywhere, the whole unit of rod and two gears acts as an idler. The function is not to drive the rod but merely to roll the unit of rod and gears simultaneously along the racks 79 and guide the parts for the particular purpose to be described. The rack teeth are quite thin and engage the gears on the pitch line with little friction. Both the racks and gears may be of economical construction such as is made by punching the parts out of sheet metal as most of the other parts are made.

In the operation of the structure, plates 1 and 2 are readily movable from fully overlapped (or closed position with the gears at the left ends of the racks) to the reading position of Fig. 1. The stop 90 on flange 75 engages stop edge 91 of latch 92, when the parts reach reading position so as to prevent further separation of the plates. By pressing down at latch end 93, plates 1 and 2 may be separated, until rod 76 engages bends 78' in end plates 78; in this position the back plates are hinged for movement to position of Fig. 2. In the reverse movements the inclined surface 77' of the part 77 will reset the latch by camming up end 93 as like part 77' will reset it if necessary in the initial separation of the plates 1 and 2. This is a simple cam arrangement for resetting the latch of Fig. 3 by the movement of the adjacent end of flange 77.

Except for the character of the latch operation, the provision for the smaller angle C in the "broken back" position of the book, and the addition of the rack and gear structure and function, it will be seen that the structure and function of this disclosure are like that of my prior patent.

In my previous construction I took particular pains to locate the latch stop near the central part of the book. This was because a latch stop located at one end would act as a pivot for the back plates to swing a considerable amount

- out of desirable alignment. In the manufacture of loose leaf books it is highly desirable and customary to use sheet metal parts and stampings. In this work it is very difficult to get mechanism to work together without giving its parts a loose fitting relation. When that is done the danger is to have the parts too loose for nice operation. There is a tendency in the manufacture to have the parts either too tight or too loose for the operations, for I have found it extremely difficult after much experience to make what I want commercially in these structures and avoid the dangers of cramping, shifting, and misalignment of parts in their operations.
- These difficulties present themselves in most serious ways with relation to such a structure as that of my prior patent. They present the problems of the present invention. These problems are to make a loose leaf structure of a particular character with overlapping back plates, easily slidable to and from closed and reading position, and pivotally movable out of the overlapped position to break the book back for page changes, and to provide this structure in economical fashion so that all its parts are loose enough to operate very freely and yet in proper alignment of parts at all times. The difficulty in holding the desired alignment is due chiefly to the necessity of providing for both a straight line movement and a pivotal movement of the same parts with a smooth transition from one to the other as wanted. If pivotal movement alone of the back plates were wanted there would be no difficulty. It is the straight line movement of the back plates that is hard to hold in alignment by economical and satisfactory means and it is still harder when it is desired to transfer the same parts from such a movement to a pivotal one.
- By the means I have described in their preferred form, I have now accomplished all that is wanted as far as I know in a loose leaf structure of the type I set out to improve. In the movement of the parts, plates 1 and 2 slide from fully overlapped position to reading position and they cannot cramp even though the pull is applied carelessly as from the line of the lower corners of the covers. Such a pull tends to separate the back plates at one end and cramp them at the other end (by pivotal movement taking advantage of all play between the parts). But with the rack and gear means supplied by me the tendency toward such cramping movement is diverted to operating the gears. They must operate in their racks and must move in unison. And so with the slightest component of force to make the gears roll in the racks they will do that and the other parts must follow since the gears and racks are aligned for parallel movement of top and bottom parts. This absolutely prevents cramping and the objectionable effects of twisting movements of the parts on careless operation by the user to open or close the structure. By making the pivotal connection of rod 76 between the back plates 1 and 2 in line with the axis of the gears 81 which roll to the outer ends of the racks 79, I have provided means for getting the equalizing movement for relative parallel movement for all parts of the back plates and also for their pivotal movement at the end of the parallel movement and without the means for controlling one movement interfering with the other but on the contrary each assisting the other at the right time of operation.

The simple structure gives me a perfect equalizer mechanism or parallel motion means having a part functioning for the pivotal movement when desired.

A further refinement in the loose leaf structure consists in the latch and its relation to the other parts. Because of the equalizer mechanism controlling the back plates I can make a simple form of latch 92 with its stop edge 91 located adjacent one end only of the back plates. This is most convenient for manipulation by simple structure as will be seen by comparing the present form of latch with that shown in my prior patent where the shock due to the latch stop was best localized at the central part of the book to avoid cramping.

The simple pivoted form of latch 92 has finger piece 93 at one end and stop piece 91 at the other end. The opposite sides of 93 are slightly tipped up (see Fig. 3) so as to reset the latch as the cam surfaces 77 and 77' at the end or corner of plate 2 move by it in either direction. This corner has the oppositely disposed cam surfaces to do this. And the inner cam surface 77 will always ride under the other end 91 of the latch slightly tipped up for this purpose (see Fig. 3) when the plate 2 starts to move inwardly. When the plate 2 moves outwardly its lower corner has a ledge 90 that will always strike the stop ledge 91 of the latch unless the finger piece is deliberately pressed down to release the latch stop. The latch shown has a tendency by slight friction at its pivot 80 to stay in the position set. But it should be noted that the latch will always be automatically reset by the movement of the plate 2 if it is not already set to act as a stop. Between the time of resetting and stop action of the latch 92 the latter will not get out of position because resetting and stopping take place almost at the same time.

Having fully disclosed my invention in the best form I now know to put it in use and some of the important advantages of its use, I desire to point out the scope of the invention in the claims without intending to limit said scope by the specific disclosure unless the words of particular claims may do so with the intention of claiming specific features in addition to claiming the invention in other and broader claims, all insofar as the prior art permits.

I claim:

1. A loose leaf structure consisting of two back plates, guide means for holding said plates during overlapped and slidable relation, sheet holding posts attached to the plates, equalizing means operable by movement of said plates for maintaining the sides of the plates parallel as they are moved to varying overlapped positions and means for holding the plates in pivotal engagement with each other when they are moved out of overlapped relation.

2. A loose leaf structure consisting of two back plates, guide means for holding said plates during overlapped and slidable relation to each other, sheet holding posts attached to said plates, equalizing means operable by movement of said plates and located within the end confines of said plates for maintaining them in side edge parallel relation at all times as they are moved to varying overlapped positions and means for holding said plates in pivotal engagement with each other when they are moved out of overlapped relation.

3. In a loose leaf structure of the kind having two back plates with associated sheet binding posts and connected together to slide into over-

lapped flat back relation and to separate and pivot into broken back relation, the combination of parallel motion mechanism attached to and operable by movements of the plates to keep the corresponding edges of said plates parallel at all times during overlapped relation and means in addition to said mechanism to connect the plates together for relatively slidable and pivotal movements.

10. 4. In a loose leaf structure, the combination of two back plates with sets of sheet binding posts, means connecting said plates together for relatively sliding and pivotal movements to position said posts as desired, said plates and connecting means having considerable lost motion as by loosely fitting parts to permit easy operation and to avoid friction, and parallel motion mechanism in part located on one plate and in part located on the other plate and operable by relatively sliding movements of the plates to accurately hold said plates from any relative movement other than parallel movement permitted by their lost motion connections.

5. In a loose leaf structure, two back plates having at their ends interengaging parts loosely fitted together to connect the plates for sliding and pivotal movements, racks and idler pinion means on said plates operable to maintain said plates in easily slidable relation to avoid cramping due to the looseness of said interfitting parts.

6. In a loose leaf structure, two back plates connected together for sliding movement, gear racks on one plate and idler gears mounted on a single idler shaft on the other plate to engage said racks, a pivotal connection for the edges of said plates operable for pivotal movement when the plates are separated, said pivotal connection having an axis coincident with the axis of said idler gears.

7. A loose leaf binder comprising a back plate having adjacent one side sheet posts mounted to overhang the plate, and an attached cover, the other end of said plate having a hook-shaped overhanging marginal portion, the outer edge of which forms a hinge eye, a hinge pintle or rod in said eye, spaced idler pinions keyed on said rod, a second back plate also having like sheet posts along one side and cover attached at one edge, slots formed at each end of the latter plate to receive the ends of said pintle and serve as hinge

parts with the latter as well as connecting means between the plates, parallel gear racks on the latter plate in engagement with said idler pinions whereby the plates are constrained to move in desired parallel relation at all times except when operating on the hinge for pivotal movement.

8. The combination of claim 7 and a latch located with parts on each plate and at one end of the binder.

9. A loose leaf structure having in combination two generally flat back plates with sheet holding posts arranged for separation by sliding and pivotal movements, means to connect said plates together for such movements and idler mechanism to restrain sliding movement of the plates to the desired parallel relation.

10. The structure of claim 9 and said mechanism including idler gear rack means on one plate and gear means on the other plate engaging said rack means.

11. In a loose leaf structure, two back plates connected together for sliding movement, a pair of spaced gear racks and a pair of idler gears mounted on said plates as an equalizing mechanism, pivotal connecting means for the edges of said plates operable for pivotal movement when the plates are separated, said pivotal means having an axis coincident with the axis of the idler gears whereby the latter may engage their racks as the plates pivot on said axis.

12. In a loose leaf structure, two back plates having sheet binding posts attached thereto and connected together for sliding movement, a pair of spaced gear racks transversely arranged on one plate, a rod rotatably mounted at the long adjacent edge of the other plate to overhang said racks, gears on said rod and connected by the latter to turn together as they engage said racks during sliding movement of the plates, pivotal means adapted to mount the ends of said rod when the plates are spread apart for pivotal movement of said plates while the gears remain in engagement with said racks, said gears, rod, and racks forming an idler equalizing means operable by the movements of the said plates to different positions for placing the sheet binding posts as desired.

JOHN SCHADE.
